DESIGN FOR A PENCIL

James Jernigan Sanders, Nashville, Tenn.

Application February 18, 1942, Serial No. 105,857

Term of patent 3½ years

To all whom it may concern:

Be it known that I, James Jernigan Sanders, a citizen of the United States, residing at 124—4th Ave. So., city of Nashville, in the county of Davidson and State of Tennessee, have invented a new, original, and ornamental Design for Pencil, of which the following is a specification, reference being had to the accompanying drawing, forming part thereof.

I claim:

The ornamental design for a pencil, as shown.

JAMES JERNIGAN SANDERS.
